UNITED STATES PATENT OFFICE

2,147,887

FOOTWEAR AND METHOD OF MAKING THE SAME

Alfred F. Donovan, Boston, Mass., assignor to
E. T. Wright & Company, Inc., Rockland, Mass.,
a corporation of Massachusetts

Application October 27, 1936, Serial No. 107,759

11 Claims. (Cl. 12—146)

This invention pertains to footwear and relates more particularly to an improved bottom structure for shoes and the like. As herein defined the bottom structure is to be regarded as 5 inclusive of the insole proper (irrespective of the material or materials of which it is composed); the shank piece or stiffener member; and a metatarsal pad;—the present invention having for its principal object the provision of a bottom 10 structure whose constituent parts are so designed and arranged as to insure accuracy in assembling them in their proper relation in the completed shoe.

In the patents to Brown Nos. 1,249,318 and 15 1,656,556, the utility of a stiff and strong shank piece and associated metatarsal pad has been pointed out. However, as a matter of factory practice it has been found quite difficult to insure accuracy in locating the pad and shank 20 piece relative to the insole proper or to each other, and, in consequence, certain of the advantages which should always be obtainable in following the teachings of said Brown patents are in actual practice sometimes partially or completely lost. Since inspection of the completed 25 shoe does not necessarily show that the parts of the bottom structure have not been properly positioned, the wearer, although expecting to receive the benefits of the Brown improvements, 30 may be deprived of such benefits and may even suffer ill effects if the shoe parts are sufficiently out of place. As above noted, the principal object of the present invention is to provide an improved bottom construction such as substantially 35 likely to insure reasonable accuracy in assembling its constituent parts, and to this end the invention contemplates the provision of accurately located positioning elements upon the insole proper to guide the operator in assembling the metatarsal pad therewith and also accurately located, 40 cooperatorable positioning elements upon the pad and shank piece whereby to assure accuracy in assembling the shank piece with the pad and insole proper. Another object is to provide an improved shank piece useful in the practice of the 45 present invention and improved means whereby the shank piece may be anchored in place and firmly attached to the other elements of the shoe bottom.

50 A further object is to provide an improved method of procedure in assembling the constituent elements of the bottom structure of a shoe so as to insure accuracy of relative position of such constituent parts.

55 Other objects and advantages of the invention

will be pointed out in the following more detailed description and by reference to the accompanying drawing wherein:

Fig. 1 is a plan view of the insole member of the shoe bottom;

Fig. 2 is a bottom view of an insole member provided with a sewing rib such as is used when the bottom structure is to form a constituent part of a welt shoe;

Fig. 3 is a section to larger scale substantially on the line 3—3 of Fig. 2;

Fig. 4 is a perspective view of a metatarsal pad, of preferred shape, designed to form one of the constituent elements of the improved bottom structure;

Fig. 4a is a bottom view of the insole member showing the metatarsal pad associated therewith;

Fig. 5 is a transverse section to larger scale substantially on the line 5—5 of Fig. 4a;

Fig. 6 is a bottom view of the insole member showing the metatarsal pad as covered and concealed by a reinforcing layer constituting an element of the insole proper;

Fig. 7 is a section to larger scale on the line 7—7 of Fig. 6;

Fig. 8 is a bottom view of the insole of Fig. 6 showing it as having been provided with a transverse shank positioning recess extending crosswise of the metatarsal pad;

Fig. 9 is a fragmentary longitudinal section on the line 9—9 of Fig. 8;

Fig. 10 is a bottom view of an improved shank piece or stiffener designed to form one of the constituent elements of the shoe bottom structure;

Fig. 11 is a plan view of the shank piece of Fig. 10;

Fig. 12 is a bottom view of the insole of Fig. 8 with the shank piece assembled therewith;

Fig. 13 is a fragmentary longitudinal section, to larger scale, substantially on the line 13—13 of Fig. 12; and

Fig. 14 is a fragmentary longitudinal section, to larger scale, substantially on the line 14—14 of Fig. 12.

Referring to the drawing, the numeral 1 designates an insole member designed to form one of the constituent elements of the improved bottom structure of a shoe, said insole member being of 50 leather or other suitable material cut to substantially the desired shape and size, and in accordance with the present invention having an elevation 2 at its inner or upper side, substantially at the junction of the shank portion and 55

forepart, designed to furnish means for manipulating or supporting the metatarsal arch of the foot of the wearer of the shoe, as described in the patent to Brown No. 1,656,556 above referred to. The insole 1 is also shaped at its shank portion to provide angularly disposed lateral portions 3 and 4 meeting at the longitudinal furrow or depression 5, the part 3 constituting the normally substantially horizontal support for the outer portion of the foot while the part 4 slopes upwardly and is designed to prevent or to some extent to remedy tendency of the foot to pronate, all as more fully described in the aforesaid patents to Brown. This shaping of the insole member 1 may be accomplished in a press and by means of dies of suitable design. The heel end of the insole 1 may be substantially flat to form the heel seat of the shoe, its junction with the shank portion being defined if desired by a line 7, consisting, for example, of spaced dots or depressions adapted to facilitate subsequent operations, although this line of demarcation is not necessary nor an essential feature of the present invention.

Referring to Fig. 2 the bottom side of this insole member 1, throughout such portion of its forepart 8 as is desired, may be furnished with transverse slashes 9 or other suitable means for making the forepart flexible, and when the bottom structure is to form part of a welt shoe, the under side of the insole will be provided with a sewing rib 10. This sewing rib may conveniently be formed by channeling operations, leaving the sewing channel 11 (Fig. 3) at the inner side of the rib and the marginal lip 12 at its outer side. This sewing rib may, however, be formed in any desired manner known to those skilled in the art.

The insole, in so far as the above description is concerned, is substantially like that disclosed in the Brown patents referred to, but in the present instance, in forming the elevation 2 at the upper side of the insole (such elevation being produced as above described by a die pressing operation) the under side of the insole is furnished with pad positioning elements designed to assist the operator in placing the metatarsal pad accurately at the proper position relatively to some fixed part of the insole. In forming the elevation 2, a corresponding recess 13, Fig. 2, is made at the under side of the insole. Preferably this recess is of more or less segmental contour, having the substantially straight side edges 14 and 15 and the curved forward edge 16, the recess being deeper at its rear end or apex, that is where the straight edges 14 and 15 meet, than at its forward edge. Preferably, coincidentally with the formation of the recess 13, there are provided three or more pad positioning elements, for example small depressions or pits 20, 21 and 22 in the material of the insole. These pits may conveniently be formed by means of pin-like projections upon the die which forms the recess 13. One of these pits 20 is preferably at the junction of the straight edges 14 and 15 of the depression with a longitudinal ridge 17 on the bottom surface of the insole, said ridge corresponding with the depression or furrow 5 which forms the line of demarcation between the angularly disposed surfaces 3 and 4. The other pad-locating pits 21 and 22 are preferably disposed adjacent to the left and right-hand corners, respectively, of the recess 13. While three such pad-locating elements are here illustrated, it is contemplated that a greater number may be provided if desired. As above described these pits 20,

21 and 22 are preferably formed coincidentally with the formation of the recess 13 and by means of the same dies. In forming the recess 13, the die press which is employed is provided with gauges for contact with the heel end of the insole 5 and with its lateral margins, so that the recess is accurately located mechanically and may always be depended upon to occupy the proper position laterally and longitudinally of the insole. Thus, likewise, the pad-positioning elements 20, 21 and 10 22 will be accurately located both laterally and longitudinally.

In accordance with the present invention a metatarsal pad 23 (Fig. 4) is provided, being designed to fill the recess 13 so as to provide for a 15 substantially level under surface at this point, although the material of the insole itself protrudes upwardly at this point. For this purpose, the pad 23, which may be made of any suitable material such as leather, leatherboard, rubber, 20 sheet cork or the like, is shaped to a generally segmental contour and size similar to that of the recess 13, having the straight edges 24 and 25 and the curved edge 26, the apex or point where the edges 24 and 25 meet being substantially 25 thicker than the curved edge so that the pad may be likened to a segmental wedge.

Having provided the recess 13 with its pad-positioning elements and having provided the pad as just described, the operator coats the wall of the 30 recess 13 with adhesive and likewise coats one side of the pad 23 with adhesive, if desired, and then positions the pad in the recess so that the apex 27 of the pad is located at the point 20 and its edges 24 and 25 substantially contact the location 35 elements 21 and 22. The adhesive is then allowed to set, thus fixing the pad to the insole proper, and by reason of the procedure above outlined the proper location of the pad is accurately assured.

In accordance with one desirable procedure, 40 although not absolutely necessary to the practice of the present invention, the insole member, forwardly of a transverse line 18 which defines the rear end of the sewing rib, comprises a layer of reinforcing material 28. This reinforcing material 45 may be cloth or any other suitable substance designed to impart toughness to the inner sole and particularly to strengthen the sewing rib so as to insure proper retention of the stitches by which the welt is secured to the latter. This reinforcing layer 28 is usually adhesively united to the insole proper, and extends across and substantially conceals the pad 23, the portion 23a of this reinforce material which overlies the pad being substantially flush with that portion of the 50 under side of the insole forwardly of the pad.

After this reinforce layer has been applied (if it is used) a transverse shank-positioning recess or slot 29 is formed at a predetermined distance from one end of the insole, preferably from the heel end 38. This transverse recess, which indents both the covering or reinforcing material 28 and the pad 23 itself, is preferably made by the use of a suitable die, in a die press mechanism or the like having gauges which contact with the 55 heel end of the insole and with the lateral edges of the latter, the die having a positioning element designed to be disposed longitudinally of the ridge 17. By the use of such a die and die press the transverse recess or slot 29 is accurately formed at a predetermined distance from the end 38 of the insole and makes a definite and predetermined angle, for example, substantially 90° with the longitudinally extending ridge 17. Preferably this recess 29 is furnished at spaced points with a pair 70 75

of elongate sockets 31 and 32, respectively, accurately positioned laterally of the insole and which in effect form deepened portions of the recess or slot,—extending well into the pad 23 but 5 preferably not entirely through the latter.

In accordance with the present invention an improved shank piece or stiffener member 33 is provided (Figs. 10 and 11). This stiffener comprises the angularly disposed portions 35 and 36, 10 respectively, which are adapted, in the completed shoe, to underlie the parts 3 and 4, respectively, of the insole proper, the included angle between the parts 35 and 36 receiving the ridge 17 of the insole. These portions 35 and 36 of the shank 15 piece meet at a longitudinally extending stiffening rib 37, the shank piece preferably being made from sheet steel or other stiff material, as for example by a die press operation. The shank piece is preferably furnished with a narrow tail portion 34 and with a wider head portion 38, here shown as of substantially triangular contour and which is adapted to contact with the triangular rear portion 23b (Fig. 8) of the pad 23, that is to say, that portion of the pad 20 which lies rearwardly of the recess or slot 29. The forward end of the shank piece is furnished with an upturned flange 39 (Fig. 11) which is designed to seat in the transverse recess or slot 29 of the pad 23, and is also preferably furnished 25 with prongs 40 designed to enter the sockets 31 and 32, respectively, in the pad. These prongs may be of such length that when driven into the substance of the pad they will provide for anchorage of the shank piece to the pad, although ordinarily these prongs merely constitute 30 positioning elements and have little actual attaching function.

For securing the forward end of the shank piece to the other elements of the bottom structure it is preferred to provide the shank piece with a patch 41 of some flexible material such, for example, as leather, textile fabric, rubber or the like. This patch is conveniently secured to the shank piece by means of rivets 42 or the like, 45 although it is contemplated that it may be secured to the shank piece by means of a powerful adhesive, such, for example, as one of the synthetic resins or rubber compounds. This patch 41 extends forwardly beyond the forward end of the 50 shank piece proper and is designed to overlie the surface 23a at the forward portion of the pad.

In assembling the shank piece with the other parts of the bottom structure it is only necessary for the operator to place the flange 39 in the recess 29, disposing the prongs 40 in the slots 31 and 32, and then to swing the rear end of the shank piece slightly in a transverse direction so as to center it properly with reference to those parts of the sewing rib between which it is disposed. For example, the shank piece may be so positioned, as shown in Fig. 12, that one of its edges engages the inner surface of the sewing rib. Since the recess or slot 29, with its sockets 31 and 32, has been accurately and mechanically 55 fixed at a definite predetermined distance from the heel end of the insole, and since the flange 39 is accurately related to the convergent rear edges of the triangular portion 38 of the shank piece, it is clear that the mere positioning of the flange 39 in the recess 29 will with certainty position the shank piece properly in relation to the metatarsal pad. The operator thus has little discretion in his location of the shank piece, and 60 since both pad and shank piece are thus positioned with certain knowledge that they occupy

the proper relationship to the other parts, it may be assumed that, with ordinary supervision, substantially perfect shoes may be made in accordance with the present method and by the use of the structural elements above described in so far as the location of the metatarsal pad and the shank piece is concerned. After the shank piece has thus been positioned, it may be permanently united to the other parts by adhesively securing the patch 41 to the reinforce member 28 (or 10 directly to the under surface of the inner sole if the reinforce is not used) while the rear part of the shank piece may be permanently secured to the rear end of the inner sole by means of tacks or other suitable fasteners passing through openings 43 provided in the tail portion 34 of the shank piece. As illustrated, the openings 43 are so arranged that a line joining them would extend diagonally with reference to the length of the shank piece, this arrangement preventing 15 undue weakening of the shank piece such as might occur if these openings were aligned transversely. As pointed out in the above-noted 20 patents to Brown, this shank piece is designed to be very stiff and in effect to extend the supporting action of the heel of the shoe forwardly 25 toward the ball of the shoe. When called upon to act in this manner the shank piece is subjected to a powerful bending stress, and when the openings 43 are aligned transversely, it sometimes 30 happens that the shank piece breaks at this point, whereas by arranging the openings as here illustrated there is less possibility of breakage.

It is further to be noted in this connection that the forward end of the shank piece, as defined by 35 the flange 39, is disposed at the transverse recess or channel 29 and that this recess constitutes what may be termed a line of weakness just at the junction of the shank and ball portions of the bottom structure, such line of weakness 40 clearly defining the forward end of the very stiff and rigid portion of the bottom structure, and setting it off from the relatively very flexible forepart. Thus this recess 29 defines the forward 45 limit of a stiff cantilever-like forward extension of the shoe heel proper which, with respect to its foot supporting function, may be likened to a "middle heel". This recess 29 thus performs two functions, to wit the accurate location of the forward end of the shank piece relatively to 50 the metatarsal pad and to form a clear line of demarcation between the stiff rear portion of the shoe bottom structure and the flexible forward portion thereof.

While I have hereinabove described certain 55 desirable embodiments of the invention by way of example, as well as a preferred method of practicing the invention, I wish it to be understood that the invention is not necessarily limited to the precise details hereinabove outlined but is to be 60 regarded as of a scope such as set forth and delineated in the accompanying claims.

I claim:

1. A shoe bottom structure comprising an insole member, a shank piece, and a metatarsal pad 65 having intersecting edges, the insole member having therein a pad-receiving recess, the insole having a plurality of spaced pad-positioning elements disposed inwardly of its margin and adjacent to the edges of the recess, said elements defining 70 intersecting lines and being operative to assist an operator in properly disposing a pad within the recess.

2. A shoe bottom structure comprising an insole member having therein a recess for the 75

- reception of a metatarsal pad, and pad-positioning depressions in the insole member adjacent to the margin of the recess.
3. A shoe bottom structure comprising an insole member having therein a recess for the reception of a metatarsal pad, and a plurality of spaced integral pad-positioning elements moulded in the substance of the insole proper adjacent to the margin of the recess.
- 10 4. A shoe bottom structure comprising an insole having a recess in its under surface for the reception of a metatarsal pad, said recess being of generally segmental contour with its apex directed rearwardly, the insole having a longitudinal ridge running rearwardly from the apex of the recess toward the heel, the material of the insole being shaped to provide pad-positioning elements, one adjacent to the apex of the recess and one at least adjacent to each lateral corner of the recess for assisting the operator in positioning a pad in the recess.
- 15 5. A shoe bottom structure comprising an insole, a metatarsal pad and a shank piece, the pad having therein a transverse slot disposed at an accurate distance from one end of the insole defining the proper location of the forward end of the shank piece, said recess having a pair of spaced elongate deepened portions, and the shank piece having a flange at its forward end which
- 20 fits within said slot, and a pair of prongs which fit into said slot-like deeper portions of the slot.
6. A shoe bottom structure comprising an insole having in its under surface a moulded-in recess of substantially segmental contour for the reception of a metatarsal pad, pad-positioning elements adjacent to the margin of the recess, a pad in said recess, means fixing the pad within the recess, the insole comprising a layer of reinforce material substantially coextensive with its bottom surface forwardly of the heel and covering the pad, there being a transverse slot extending upwardly into said reinforce material and pad, said slot being at an accurate distance from the rear end of the insole and constituting the locus for the forward end of a shank stiffener.
- 25 7. A shoe bottom structure comprising an insole having in its bottom surface a moulded-in recess for the reception of a metatarsal pad, pad-positioning means adjacent to the margin of the recess, and a longitudinally extending ridge for the reception of the angle of a transversely angular shank piece, and a pad fixed in the recess, the insole comprising a layer of reinforce material substantially coextensive with its bottom surface forwardly of the heel and concealing the pad, there being a transverse slot extending into the reinforce material and pad at an accurate distance from the heel end of the insole, and a shank stiffener of transversely angular cross sec-
- tion having a positioning flange at its forward end disposed in said transverse slot and receiving the longitudinally extending rib of the insole in the included angle between its lateral portions.
8. Method of making a bottom structure for a shoe which comprises as steps, providing an insole with pad-locating means, assembling a metatarsal pad with the insole and positioning the pad as determined by said locating means, permanently attaching the pad to the insole when so positioned, providing a transverse slot in the pad at an accurately predetermined distance from an end of the insole, providing a shank stiffener having a positioning element, assembling the stiffener with the insole so that its positioning element is disposed in the slot in the pad, and permanently uniting the stiffener to the insole.
- 10 9. Method of making a bottom structure for a shoe which comprises as steps providing an insole having a reinforce layer at its under side, forming a transverse slot in said reinforce layer located at a definite and accurately predetermined distance from one end of the insole, providing a shank stiffener having a positioning element adjacent to its forward end, assembling the shank stiffener with the insole so that its positioning element is disposed in the slot in the reinforce layer of the insole, and permanently uniting the shank stiffener to the insole.
- 15 10. A shoe bottom structure comprising an insole, a metatarsal pad and a shank piece, a layer of reinforce material underlying the pad and overlying the forward portion at least of the shank piece, there being a transverse recess in the reinforce layer and the pad, said recess being disposed at an accurate distance from one end of the insole and defining the proper location for the forward end of the shank piece, said recess having a pair of spaced elongate deepened portions and the shank piece having an upturned flange at its forward end which engages the recess, and a pair of prongs which extend upwardly into the respective deepened portions of the recess.
- 20 11. Method of making a bottom structure for a shoe which comprises as steps providing an insole and a metatarsal pad, applying the pad to the under side of the insole, applying a reinforce layer to the under side of the insole so as to cover the pad, forming a transverse recess in the reinforce layer and the pad at a definitely and accurately predetermined distance from one end of the insole, providing a shank stiffener having a positioning element adjacent to its forward end, assembling the shank stiffener with the insole so that its positioning element is disposed in said recess, and permanently uniting the shank stiffener to the insole.

ALFRED F. DONOVAN.
